[57] **CLAIM**

The ornamental design for a multi-purpose holder for attachment to the dashboard of an automobile, as shown and described.

DESCRIPTION

FIG. 1 is a perspective view of a multi-purpose holder for attachment to the dashboard of an automobile, showing my new design;

FIG. 2 is a top plan view thereof on a reduced scale;

FIG. 3 is a front elevation view thereof on a reduced scale; and

FIG. 4 is a right side elevation view thereof on a reduced scale.

The broken line showing of environmental structure in FIGS. 1 and 4 of the drawing is for illustrative purposes only and forms no part of the claimed design.
